(57) **CLAIM**

The ornamental design for a tubing and corner cover for a tarp enclosure, as shown and described.

DESCRIPTION

FIG. 1 is a tridimensional view of the tubing and corner cover for a tarp enclosure in accordance with the present design;

FIG. 2 is a front elevation view thereof, the bottom plan view being a mirror image of FIG. 2;

FIG. 3 is a rear elevation view thereof, the top plan view being a mirror image of FIG. 3; and,

FIG. 4 is a left side elevation view thereof, the right side elevation view being a mirror image of FIG. 4.

The broken lines in the drawings illustrate portions of the tubing and corner cover for a tarp enclosure and form no part of the claimed design. The solid lines rendered in the drawings illustrate the claimed design. The areas adjacent to the solid line subject matter form no part thereof.
